GLASS WASHING MACHINE BASE

John F. Gallo, 3530 19th Ave., Kenosha, Wis. 53140

Filed Sept. 1, 1965, Ser. No. 86,795

Term of patent 14 years

(Cl. D49—1)

FIG. 1

FIG. 2

FIG. 3

FIG. 4

FIG. 1 is a side elevational view of a glass washing machine base, showing my new design;

FIG. 2 is a top plan view;

FIG. 3 is an end elevational view, and

FIG. 4 is an opposite end elevational view.

I claim:

The ornamental design for a glass washing machine base, substantially as shown.
